UNITED STATES PATENT OFFICE.

ROBERT M. McEWEN AND ALVA McEWEN, OF MCCOMB, MISSISSIPPI.

HINGE CONSTRUCTION.

Application filed February 14, 1927, Serial No. 168,217. Renewed November 21, 1928.

This invention relates to improvements in hinges more particularly adaptable for use in connecting the sections of false floors used in refrigerator cars and the like.

- 5 A further object of this invention is the provision of an improved hinge adapted to be used in connecting the sections of ventilating flooring of refrigerator cars and the like, so that the sections of the said flooring may 10 be positioned to act as flooring in the car, against liability of relative shifting; or so that one of the sections may be collapsed on top of the other out of the position of the doorway, which is desirable under certain 15 circumstances understood by those skilled in the art; and so that the sections of the flooring may be compactly collapsed together for positioning in an out of the way location where the same will occupy but little space. 20 A further object of this invention is the provision of a reversible type of hinge, including members adaptable for connection together in a novel relation to each other and to a pair of sections to be hinged together. 25 Other objects and advantages of this invention will be apparent during the course of the following detailed description.

In the accompanying drawing, forming a part of this specification, and wherein similar reference characters designate corresponding parts throughout the several views,

Figure 1 is a plan view of a pair of sections of car ventilating flooring, in an extended connected relation as they will be positioned 35 when in use in a refrigerator car or the like.

Figure 2 is a fragmentary side elevation of details of the improved hinge when the sections which it connects are extended for use.

Figure 3 is a position showing the hinge 40 when one section is folded inoperatively on another section.

Figure 4 is a view showing the position of the hinge when the sections which it connects are compactly collapsed for packing or storage.

Figure 5 is a sectional view taken substantially on the line 5—5 of Figure 1.

Figure 6 is a transverse sectional view substantially on the line 6—6 of Figure 4.

50 In the drawing, wherein for the purpose of illustration is shown only a preferred embodiment of the invention, the letters A and B may generally designate sections of false or ventilating flooring which are adapted to 55 be connected by the improved hinges C in such relation that the flooring sections A

and B may be extended in the same plane, or may be collapsed in top surface facing relation, or may be collapsed in compact bottom surface facing relation.

60

The section A which may be referred to as a main section is constructed as in conventional manner, with longitudinal spaced parallel stringers 10 and 11, having the cross platform pieces 12 secured thereto in any 65 approved manner, in preferably edge spaced relation at right angles to the stringers 10; it being understood that the stringers 10 and 11 depend below the under surface of the cross pieces 12.

70

The section B may be referred to as a door section adapted to be placed in position between the opposed doors on a refrigerator car or the like, so that it may be conveniently removed or folded back upon the section A, 75 as will be well understood by those skilled in the art. The section B preferably includes stringers 14 and 15, having the cross platform pieces 17 connected thereon in spaced relation. The cross pieces 17 are so connect-

80

ed upon the stringers 14 and 15, that the latter when hingedly connected with the stringers 10 and 11 of the section A, are out of longitudinal alignment with the stringers 10 and 11 to permit the stringers 10 and 14 and 11 85 and 15 to be collapsed side by side with the under surface of the sections A and B in facing relation, in the relative position illustrated in Figures 4 and 6.

85

Referring to the hinge construction C, a 90 pair of the same are provided for the sections A and B, one hinge connecting the stringers 11 and 15 and the other hinge B connecting the other stringers 10 and 14 as is illustrated in Figure 1 of the drawings. The hinge C includes the elongated bodies or shanks 20 and 21, which are preferably straight for the major length thereof, and adjacent their pivoted ends they are provided with offset ends 22 and 23 respectively, 95 which are in a J-shaped relation with the shank body; the ends 22 and 23 being transversely arranged in an acute angle relation to the shank portions 20 and 21 with which they are respectively integral. At the outer ends of the end portions 22 and 23 the same are connected by means of a pivot bolt or pintle 25, and to space the ends 22 and 23 from rubbing on each other a hub 26 may be provided about the opening 27 in the end 22, 100 which abuts against the facing side of the end portion 23 of the section 21; and the end 23

105

110

may have a similar hub 29 thereon facing away from the end portion 22, this hub 29 having a passageway 30 therethrough through which a reduced hub 31 of the end 22 extends; it being understood that the passageway 27 thus receives in contact therein the pintle bolt or rivet 25, as is illustrated in Figure 5 of the drawing, and a suitable washer 33 may be provided for cooperating 10 with the head end of this pintle bolt or rivet 25.

It is thus to be noted that the hinge parts 20 and 21 are connected by means of the pintle 25 at a location offset from the axes 15 of the portions 20 and 21, and when the end portions 22 and 23 are in adjacent conforming transverse alignment the bodies 20 and 21 of the hinge C are in a divergent relation, as illustrated in Figure 2 of the drawing. 20 Near their outer ends the body portions 20 and 21 are provided with transverse hub extensions 40 and 41, having passageways therethrough for receiving pivot pins or bolts to be subsequently mentioned. At their extreme ends the bodies 20 and 21 are provided 25 with reduced obtusely arranged ends 43 and 44, the edges 45 of which are obtusely arranged, out of alignment with the edges 46 of the bodies 20 and 21, to accommodate 30 an arrangement of the sections A and B obvious from the illustration.

Referring to the matter of attachment of the hinge parts on the sections A and B, the stringers 10, 11, 14 and 15, on the sides of 35 which the hinges are connected, are provided with angle-shaped wear plates 50, which are secured by means of bolts 51 to the stringers, and which provide side wear plate portions along the sides of the stringer and a top wear plate portion against which the edges 45 and 46 of the hinge bodies abut during positioning of the sections A and B in various collapsed or extended relations. 40

The bodies 20 and 21 of the hinge C are pivotally connected by detachable bolts or pintles 55 to the respective stringers of the sections A and B, so that each hinge has a body portion 20 thereof connected to an outer or inner side of the stringer of one section and the body portion 21 of said hinge is connected to the inner or outer stringer of the other section, so that in any event the hinge C will offset the stringers of the sections A and B in a non-aligning relation, so that the stringers may 55 be collapsed parallel with the under surfaces of the platform sections facing, as is illustrated in Figure 4 of the drawing.

During the normal extended positioning of the platform sections A and B it is to be 60 noted that the hinge bodies 20 and 21 are pivotally connected by the pintles or bolts 55, so that the bodies 20 and 21 converge downwardly from said pintles 55, and the end portions 22 and 23 are upturned in transverse 65 conforming relation, and the pintle 25 is

disposed below the top surface of the platform sections, now disposed in the same plane. In position it is to be noted that the outwardly facing edges 45 and 46 are spaced below the downward surfaces of the wear angles 50. 70 When it is desired to swing the section B out of the doorway of a car, upon the section A, without moving the latter, it is merely necessary to lift the section B and incident to the arrangement of the hinges the bodies 20 75 and 21 will pivot on the pintles 55 and permit the top surfaces of the cross platform pieces 12 and 17 of the sections A and B to come into abutment, as is illustrated in Figure 3, and this places the stringers of the section B uppermost, and the edges 46 of the bodies 20 and 21 abut against the under surfaces of the top flanges of the wear angles 50, to take the wear and limit liability of damage to the platform or floor sections incident to such collapsing. 80 In event it is desired to remove the floor sections A and B for storage, or to an out of the way location, it is merely necessary to swing the same inwardly with their under surfaces in facing relation, and since the stringers are 85 out of aligning relation they may be collapsed parallel side by side, and in this position the edges 45 of the bodies 20 and 21 come into abutment with the under surfaces of the top flange of the wear angles 50, as illustrated 90 in Figure 4, and the bodies 20 and 21 of the hinge parts are in an X-shaped relation.

From the foregoing description of this invention it is apparent that a novel type of hinge has been provided, particularly well adapted for use in connecting a pair of floor sections of the general character referred to. 100

Various changes in the shape, size, and arrangement of parts may be made to the form of invention herein shown and described, 105 without departing from the spirit of the same or the scope of the claims.

We claim:

1. In a hinge the combination of a pair of elongated shanks, said shanks each having an offset end portion, means pivotally connecting the outer ends of said offset end portions, so that each of said end portions may swing to either side of the axis of the other, said shanks at the opposite ends being provided with end portions extending in a direction opposite on the respective bodies to the first mentioned offset end portions. 110

2. As an article of manufacture a hinge construction comprising a pair of substantially J-shaped members including elongated substantially straight body portions having shorter transverse acute offset ends, pintles pivotally connecting the outer ends of said offset ends, said elongated bodies having substantially straight counter moving edges from their offset ends towards their opposite ends and at their opposite ends having obtusely arranged straight edges. 120

3. In a device of the class described the 125

- combination of a pair of sections having depending stringers therebelow, a hinge including a pair of substantially J-shaped shanks including elongated straight body portions and transversely offset end portions, a pintle connecting the offset end portions at the outer ends thereof, and pivot members pivotally connecting said shanks at their opposite ends on the stringers of said sections.
- 5 4. In a device of the class described the combination of a pair of sections having depending stringers therebelow, a hinge including elongated straight body portions and transversely offset end portions, a pintle connecting the offset end portions at the outer ends thereof, and pivot members pivotally connecting said shanks at their opposite ends on the stringers of said sections, said shanks having surfaces thereon adapted to engage
- 10 the sections when the same are collapsed.
- 15 5. In combination with a pair of sections each including a stringer, and hinges connecting the stringers of one section with the stringers of the other section with the
- 20 25 stringers of the said sections in offset alignment, said hinges each including substantially a pair of J-shaped sections pivotally

connected together at their free ends and pivotally connected at their opposite ends to the stringers to permit collapsing of the sections at either side of each other.

6. In a hinge construction a pair of sections, a hinge including a pair of hinged parts with each part including an elongated body with transverse offsets at the ends thereof offset in opposite directions, means pivotally connecting said parts of the hinge together at the outer ends of similar offsets, and means pivotally connecting the hinge parts to said sections at the juncture of the bodies thereof with the other offsets so that the sections may be moved to a collapsed relation at either side of the plane of the other in a relation that when collapsed together in one position the elongated bodies will form an abutment against said sections and when collapsed together at the opposite sides said sections will have their hinged parts in position so that the bodies are in an X-shaped relation with the offset ends thereof adjacent the respective pivots on said sections in abutment with said sections.
